UNITED STATES PATENT OFFICE.

LESLIE SALTER, OF VALLEJO, CALIFORNIA.

VISE-OPERATOR.

1,393,834.

Specification of Letters Patent. Patented Oct. 18, 1921.

Application filed December 13, 1920. Serial No. 430,379.

To all whom it may concern:

Be it known that I, LESLIE SALTER, a citizen of the United States, residing at Vallejo, in the county of Solano and State of California, have invented a new and useful Vise-Operator, of which the following is a specification.

The present invention relates to an improvement on the common bench vise and its object is to provide a power attachment which is easy to install on the bench vise now in common use and enables the operator to open and close the gap between the jaws by bearing down on a lever with either 15 the toe or the heel of his foot.

The advantages of such as attachment are obvious. Where the object to be inserted between the jaws is heavy, the operator often finds it difficult to hold the object with one 20 hand while using the other hand for turning the lever which closes the jaws against the object. With my attachment he may conveniently hold the object with both hands and press down on the lever with 25 his foot which will set the traveling jaw in motion and cause the same to either close in on the object or to release the same. Where small objects are to be handled in 30 large quantities, my attachment will enable the operator to use both hands for the insertion and removal of the objects, thus saving a large number of motions and interruptions which are at present required for 35 opening and closing the vise by hand and for laying down and taking up tools.

I attain these objects by the mechanism illustrated in the accompanying drawing, in which—

Figure 1 is a side elevation, partly shown 40 in section, of a bench vise as now in common use.

Fig. 2 is a side elevation, partly shown in section, of a bench vise with my attachment fastened to it.

Fig. 3 is a rear view of the attachment.

Fig. 4 is a detail view of a modification of the drive shaft.

Similar numerals refer to similar parts throughout the several views.

1 is a bench vise of the type now in common use, consisting principally of the stationary jaw 2 and the traveling jaw 3. The stationary jaw 2 rests on the base 4, which is bolted to the top of the bench 6, as shown 50 at 7, and is provided with a rectangular, horizontal hole 8, into which fits slidably the 55 rectangular extension 9 of the traveling jaw 3. Extension 9 is hollow and open at the bottom so as to clear the nut 11 which is inserted in a groove 12 of the stationary jaw 60 and firmly held in its place by a pin 14. In the nut turns the screw 16, provided at its outer end with a hand lever 17 and mounted in a bearing in the outer wall 18 of the traveling jaw 3. A collar 19 on said 65 screw, bearing on one side against a recess in the outer wall 18 and on the other side against a guard 21, forces the traveling jaw to follow the motions of the screw 16.

To attach my device to this vise I remove 70 the hand lever 17, key the screw 16 to the traveling jaw, as shown at 22, and take the nut 11 out of its groove in the stationary jaw. I then rigidly fasten to the rear end 23 of the stationary jaw 2 the housing 24, as shown 75 at 26. The housing extends backward far enough to allow the vise to be closed without the extension 9 coming in contact with the back wall 27 of the housing. In the back wall 27 is rotatably mounted, in bearings 80 28 and co-axially with the screw 16, the shaft 29, prevented from sliding in its bearing by two collars 31 and 32. The part 33 of said shaft, extending inwardly, is hollow 85 and threaded on the inside so as to be adapted to engage the screw 16 and to work 90 said screw, and with it the traveling jaw, backward and forward. Rotary motion may be imparted to the shaft 29 in any known manner. I consider my invention particularly useful in those shops which are equipped with compressed air and for that reason have selected, for the purposes of 95 this illustration, an air motor 31 as the driving power. The latter drives the shaft 29 by means of a worm 35 mounted on shaft 33 engaging the worm gear 34 mounted on 100 said shaft 29. The air motor is controlled by a lever 36, pivoted centrally, the two arms of which are connected with rods 37 and 38. A pull on rod 37 revolves the shaft 29 in one direction and a pull on rod 38 revolves it in the opposite direction. Each of the free ends of the rods 37 and 38 is fastened to one of the arms 41 and 42 of a lever 43, centrally pivoted on the standard 105 44 secured to the base plate 46, which latter plate is screwed to the floor in a place with convenient reach of the foot of the operator. Each arm of the lever 43 is supported by an expansion spring 47 also resting on the base plate 46. These two springs 110

normally keep the lever 43 in a horizontal position, and in this position the air supply to the air motor is shut off. When the operator presses down with his foot on arm 41 of the lever 43, the rod 37 pulls on one arm of the lever 36, thereby supplying air to the air motor and causing the traveling jaw to move in one direction, say, toward the stationary jaw 2; and vice versa a pressing 10 down on arm 42 of the lever causes jaw 3 to move in the opposite direction, that is, away from the stationary jaw.

It can be easily seen that similar arrangements for the moving forward and backward of the traveling jaw can be made for any other power which may be at the disposal of the operator and for belt connections to a main shaft.

A further advantage of a power attachment as above described is that an extension of the shaft 33, which is, under normal conditions, within handy reach of the operator, may be used as shaft for rotating tools such as an emery wheel, a buffering wheel or circular saw, as shown in Fig. 3, in which 48 signifies a circular saw, 49 a buffering wheel and 51 an emery wheel; a drill 50 may be inserted into the end of the shaft.

I realize that the greatest amount of power 30 will be needed at the instant when the jaws are to be separated, that is, at the time when the traveling jaw is to start on its backward travel. Since this is the very time when the supplied power is the least effective, it may be found that the power is not sufficient to separate the jaws. To overcome 35 this difficulty the shaft 33 may be separated

into two parts, as shown in Fig. 4, part 52 to be provided with a thread 53 between two shoulders 54, and part 55 to have an 40 enlarged hollow extension 56 adapted to clear the shoulders 54 and an inside threaded collar 57 at the end of the extension adapted to engage the thread 53. The collar 57 being shorter than the distance between the two shoulders 54, part 55 is allowed to make a number of revolutions before engaging part 52 of the shaft and thus to acquire a momentum sufficient to overcome the initial resistance of the jaws to 50 their separation.

I claim:

1. A vise, comprising a stationary jaw, a traveling jaw slidably mounted therein, a screw rigidly secured in said traveling jaw, 55 a shaft mounted in said stationary jaw aligned with said screw having a threaded sleeve adapted to engage said screw, means for rotating said shaft so as to slidably move said traveling jaw in said stationary jaw 60 and a spring balanced foot lever adapted to control said means.

2. A vise, comprising a stationary jaw, a traveling jaw mounted therein, a screw rigidly secured in said traveling jaw, a housing 65 rigidly fastened to said stationary jaw, a shaft mounted in said stationary jaw aligned with said screw having a threaded sleeve adapted to engage said screw, means for rotating said shaft so as to slidably move said 70 traveling jaw in said stationary jaw and a spring balanced foot lever adapted to control said means.

LESLIE SALTER.
